VENTING BUNG

Application filed March 3, 1931. Serial No. 519,876.

This invention relates to bungs, and has particular reference to a venting bung designed to fit the bung hole of a container in which wine or other liquids are contained which are in the course of fermentation, in order to relieve the container of pressure developed therein by the fermentation process.

The invention contemplates among its objects the provision of a venting bung provided with means which admits of the relief of pressure but prevents the unintentional ingress of air or foreign matter to the container through said bung while admitting of the intentional introduction of substance to the container without necessitating the removal of the bung.

More specifically, the invention resides in a bung having an axial passage extending completely therethrough, together with valve means swingingly supported by the upper end of the bung and cooperating with the upper end of the passage to normally close the same, said valve means being so mounted as to permit of its disposition in an out-of-the-way position when it is desired to introduce substances through the passage.

Other objects reside in the comparative simplicity of construction of the bung, the economy with which it may be produced and the general efficiency derived therefrom.

With the above recited and other objects in view, reference is had to the following description and accompanying drawing, in which there is exhibited one example or embodiment of the invention, while the claims define the actual scope of the same.

In the drawing:

Figure 1 is a vertical sectional view through a bung constructed in accordance with the invention.

Figure 2 is a plan view thereof.

Referring to the drawing by characters of reference, 5 designates the bung body, which is preferably constructed of wood and which is of the usual tapered or frusto-conical construction having an upper major diameter 6 and a reduced lower diameter 7, whereby the same is adapted to fit a large variety of bung holes. The body 5 is formed with an axial passage 8 extending completely therethrough

and a bushing 9, preferably of metal, is recessed in the upper end of the body and has a bore 10 coinciding with the axial passage 8. A split band 11 is clamped around the periphery of the body 5 and is disposed flush with the upper end thereof. In practice, the split band is preferably recessed within the countersunk peripheral portion 12 of the body, and said band is formed with outwardly directed ends 13 having reversely bent extremities 14 disposed parallel to and in flat contact with the ends 13 to define substantially parallel apertured ears for receiving therethrough a bolt 15 having a head 16 at one end and a nut 17 at the opposite end to accomplish the clamping of the band around the body 5. The extremities 14 may be formed at their free ends with circumferentially extending terminals 18 which are disposed in contact with the band and serve to reinforce the ears at their juncture with the band. At a point diametrically opposite the ears, the band is provided with an upstanding strap 19, the upper end of which is reduced and formed into a pintle roll 20. An arm 21 is provided at one of its ends with spaced pintle rolls 22 which straddle the pintle roll 20 and which receive, together with the pintle roll 20, a hinge pintle 23 whereby the arm is fulcrumed for swinging movement.

In order to close the upper end of the axial passage 8, a valve 25 is loosely carried by the arm intermediate its end so that the same has a limited relative movement with respect to the arm. As illustrated, the valve 25 is attached to the arm by means of a headed screw 26 which extends loosely through an aperture 27 in the arm 21 and is anchored in the valve. The valve is preferably formed with a semi-spherical or equivalent shaped lower end 28, whereby it effectually seats against the bushing 9 by gravity when the bung is arranged in its usual upright position.

In order to provide means which permits of the use of the bung in any position and at the same time to serve as a yieldable securing means for holding the valve in seated condition, a coiled contractile spring 30 is provided, the lower extremity of which is formed into an eye 31 engaged over the bolt shank 100

15 and the upper end of which spring is formed into an eye 32 which is adapted for engagement over the upturned reduced extremity 33 of the arm 31.

5 In use, when the bung is arranged within the bung hole of a container and is disposed in a vertical position as illustrated in Figure 1, the spring may be disengaged from the extremity of the arm 21 and the weight of the 10 valve 25 and the arm will serve to permit gravitational seating of the valve. As internal pressure develops within the container, it is obvious that this pressure will be relieved periodically by lifting the valve and valve 15 arm to permit of the escape of the pressure without allowing air or foreign matter to enter through the passage 8. It is also apparent that when necessary, water or other substances may be introduced without removing 20 the bung, by lifting or swinging the valve arm and valve to an out-of-the-way position. After the development of internal pressure is retarded, the spring may be engaged with the arm, it being evident that excessive pressure 25 will be relieved by lifting of the valve against the action of the spring. If it is desired to use the bung in other than a substantially vertical position, the spring 30 may be engaged with the arm to hold the valve 30 in seated relation.

It will be observed that the band 11 and bushing 9, in addition to performing their other function, serve in the capacity of means for reinforcing the upper end of the bung to 35 increase its resistance against impact when hammering the same into a bung hole.

While there has been illustrated and described a single and preferred embodiment of the invention, it is to be understood that 40 variations and modifications which fall within the scope of the same may be resorted to when desired.

What is claimed is:

1. A venting bung including a body having 45 an axial passage extending completely therethrough, a split band surrounding the upper end of the bung body, an arm fulcrumed to said band and a valve rockably carried by the arm for movement bodily therewith to and from a seated relation to the upper end of the passage.

2. A venting bung including a body having 50 an axial passage extending completely therethrough, a bushing recessed in the upper end of the body having a bore coinciding with the passage, a split band surrounding the upper end of the bung body, an arm fulcrumed to the band and a valve rockably carried by the arm for movement bodily therewith and for relative movement to and from a seated relation to the bushing.

3. In a venting bung, a bung body having 55 an axial passage, an internal bushing at the upper outlet end of the passage, a split band 60 clamping surrounding the upper end of the

bung body and valve means swingingly carried by said ring and normally seated on the bushing for closing the outlet end of said passage.

4. A venting bung including a body having 65 an axial passage extending completely therethrough, a split band surrounding the upper end of the bung body, an arm fulcrumed to said band, a valve carried by the arm for movement to and from a seated relation to the upper end of the passage, said split band having outwardly projecting spaced parallel ears, means extending therethrough 70 for clamping the band in position and contractile means supported by said clamping means and detachably engaged with the free end of the arm for yieldably holding said arm in a normal position to seat the valve.
